AUTOMATIC ELECTRIC COUPLER

George W. Gobrecht, Broomall, Pa., assignor to Walton Products, Inc., Newtown Square, Pa., a corporation of Pennsylvania

Filed Aug. 30, 1963, Ser. No. 305,604

6 Claims. (Cl. 339—48)

This invention relates to automatic electric couplers, for use with hook or other automatic mechanical couplers that lock tightly when coupled, for automatically coupling electric service lines of railway cars as the cars are mechanically coupled to each other.

The primary object of the present invention is to provide an automatic electric coupler, the contacts of which can be applied and removed as a unit for repair or replacement in a minimum of time and without use of special tools.

Another object of the invention is to provide an automatic electric coupler which has its contacts so mounted as to be applicable and removable as a unit without disturbing the mounting of their housing on the associated automatic mechanical coupler.

An additional object of the invention is to provide an automatic electric coupler wherein the contacts are connectable to the service lines of the associated car through a readily accessible common plug, thereby enabling the lines and contacts to be disconnected for removal of the latter as a unit simply by unplugging the plug.

A further object of the invention is to provide an automatic electric coupler whose contacts are so arranged and constructed as to facilitate their connection to electrical leads and render them substantially impervious to service wear.

Other objects and advantages of the invention will appear hereinafter in the detailed description, be particularly pointed out in the appended claims and be illustrated in the accompanying drawings, in which:

FIGURE 1 is a plan view of a subway type automatic coupler assembly including a pair of the automatic electric couplers of the present invention;

FIGURE 2 is a fragmentary side elevational view on an enlarged scale of a preferred embodiment of the coupler of the present invention removed from the assembly of FIGURE 1;

FIGURE 3 is a vertical sectional view taken along lines 3—3 of FIGURE 2;

FIGURE 4 is a rear elevational view of the coupler of FIGURE 2 with portions broken away;

FIGURE 5 is a fragmentary horizontal sectional view on an enlarged scale taken along lines 5—5 of FIGURE 3;

FIGURE 6 is a fragmentary exploded view of the electric coupler on the scale of FIGURE 2 and with parts removed to more clearly show the mounting for the insulator block;

FIGURE 7 is a fragmentary vertical sectional view on an enlarged scale taken along lines 7—7 of FIGURE 4 and showing the details of a preferred form of plug-in connector for connecting the contacts with the electric lines on a car; and

FIGURE 8 is a front elevational view of the connector of FIGURE 7 with the plug removed.

Referring now in detail to the drawings in which like reference characters designate like parts, the improved automatic electric coupler of the present invention, designated as 1, is designed primarily for use as part of an automatic railway coupler assembly 2 by which train air and electric service lines are automatically coupled or connected between cars simultaneously with the mechanical coupling of the cars. Such assemblies are now

2

found mainly on subway cars in which the electric couplers are customarily mounted singly or in pairs, respectively, below and at sides of the mechanical couplers at the ends of a car.

5 A typical coupler assembly 2 is illustrated in FIGURE 1 in which a pair of the improved electric couplers 1 are bolted or otherwise suitably mounted on opposite sides of an automatic mechanical coupler 3 of the hook type, such as shown in Cope application Ser. No. 283,395, filed on May 27, 1963. The illustrated assembly also includes a draft arm 4 carrying and pivotally connected to the coupler and pivotally or swivelly connected in turn to the car (not shown) through a mounting 5 secured to the underside thereof.

10 Each of the illustrated pair of automatic electric couplers 1 is comprised of a substantially rectangular box or housing 6 mountable on a side of and preferably disposed parallel to the coupler 3, as by having its inner or coupler-facing side 7 boltable or otherwise securable to the side of the coupler, at the front directly and at the rear through a fixed Z or other suitable lateral spacer or bracket 8. Conveniently fabricated of sheet metal, the box 6 is open at the front and inside or within its front end 9 has fixed to or rigid with it a one or plural-piece 15 backing or positioning plate or flange 10 which extends around and stands from the sides of the box. For both fixing it to the box 6 and rigidifying the latter, the backing flange 10 may be formed as the inner, standing leg of an angle backing or positioning member 11 20 fitting or received in the open front end 9 of the box, the other or outer leg 12 of which abuts or lies against and is welded or otherwise secured to the sides of the box.

25 Also received in the front end 9 of the box 6, but in this case releasably, is a base 13 of a rigid insulator block 14 of rubber or other suitable insulating material. Generally, rectangular in cross-section to conform to the preferred shape of the box 6, the base 13 of the insulator block 14 is slideably insertable into the open end 9 of the box 6 and fits or seats within the outer flange 12 of the positioning member against or backed by the inner or backing flange 10. The preferred insulator block is of stepped formation and formed, in addition to the base or base part 13, of a head or outer part 15 which projects or is disposed outwardly of or beyond the outer end 9 of the box 6. Rectangular in cross-section but relatively reduced and inset transversely within the base 13, the head 15 is bounded by a rectangular recess 16 in which releasably fits an angle retainer or retainer frame 17 having a rectangular collar 18 surrounding the head and, at the rear of the collar, a transversely outstanding peripheral flange 19 abutting against or engaging the outer face or end 20 of the base.

30 35 40 45 50 55 60 65 70 75 80 85 90 95 100 Longitudinally aligned apertures 21 and 22 are provided, respectively, in the base 13 and the peripheral or base flange 19, preferably one on each side, for receiving correspondingly positioned mounting or positioning posts or lugs 23 fixed and projecting outwardly substantially normal to the backing flange 10 in the box 6. On assembly, the insulator block 14 is held in the box 6 between the retainer 17 and the backing flange 10 by means carried by the posts 23, the latter for this purpose preferably being radially or transversely slotted to receive flat, wedge-shaped locking keys, wedges or knock-outs 24 which are bent after insertion to prevent accidental removal and can be removed simply by knocking or tapping them out of their slots. Since there are no tensile forces on the coupler and compressive forces are transmitted from the pins through the insulator block 14 directly to the box 6, all the keys 24 actually need do is to hold the block in assembled relation when the coupler is uncoupled. Ordinarily,

it will be desirable that the insulator block 14 be insertable only one way into the box and the posts 23 can be made to perform this additional function by offsetting one or more and the corresponding apertures 21 and 22 from the related transverse centerline of the box.

Confined laterally or transversely within and interrupting the usually flat front face or end 25 of the outer part 15 of the insulator block 14 and extending normal to the face through the block are a plurality of laterally or radially spaced, preferably cylindrical, perforations, apertures, holes or drillings 26. In each of the perforations 26 is received or seats a contact pin or contact 27 for completing the circuit between cars or one of the train electric service lines by contacting a corresponding contact of the mating electric coupler of another car. While the number and arrangement of the contact pins 27 will depend on the particular installation, a typical installation requiring the coupler assembly 2 to have the illustrated pair of electric couplers 1, may have thirty-two contacts in one, as in the coupler shown in detail, and nineteen in the other, the contacts in each being arranged in vertically spaced rows.

Each of the contact pins 27 preferably is cylindrical and has, adjacent its front end 28, an annular shoulder or abutment 29 interposed axially between its tip 30 and its stem 31 and of larger diameter or cross-section at least than the stem and usually than the tip, as well. Correspondingly, each perforation 26 has a rear part 32 of a diameter to slideably receive the stem 31 of the related pin 27 and, forwardly, is enlarged to provide a socket or front part 33 for slideably receiving the pin's shoulder 29. Axially movable or reciprocable in its aperture 26 and guided in such movement by the sliding engagement of its shoulder 29 and stem 31, respectively, with the front and rear parts 33 and 32, each pin 27 is urged forwardly or outwardly by spring means suitably in the form of a coil spring 34 contained in the socket 33 about the stem 31 and acting between the shoulder and a rear wall or rear part 35 of the base 13 of the insulator block 14 in which the restricted rear part of 32 the aperture 21 is formed. Preferably unitary or of one-piece construction and formed mainly of brass or like material, each pin 27 is both limited in its forward movement and removably or releasably held in its aperture 26, conveniently by a washer 36 encircling its stem 31 at the rear of the insulator block 14 and in turn normally rearwardly engaged by a center or like pin 37 extending radially through the stem.

Rather than mold it in one piece with the nicety of counterboring that this would entail in forming the apertures 26, the preferred insulator block 14 has its rear wall 35 containing the relatively restricted rear parts 32 of the apertures 21 formed separately. With this two-part construction, it is possible for each part of the block to be drilled through to one diameter and the parts then to be aligned and screwed or otherwise connected together, with assurance that the sockets 33 of the two-diameter apertures 26 will be of uniform depth.

As in a conventional automatic electric coupler, the purpose of the springs 34 is, by projecting the contacts 27 initially beyond the positions they occupy on coupling, to make available a spring force for maintaining electrical contact between mated electric couplers over the limited range of relative movement permitted by the associated mechanical couplers 3 and despite some service wear. However, while the contacts of both the improved and conventional couplers are relieved from wear due to arcing by the usual drum switches (not shown) included in an installation, the conventional brass contacts are still subject to mechanical wear due to friction with consequent serious limitation on their service life, a limitation but little affected by the conventional practice of silvering the tips. By contrast, the contacts 27 are given an extended service life without detriment to their electrical properties by forming their usual flat and radially dis-

posed front ends 28, in part and preferably centrally of a material, such as tungsten carbide, which is comparable in conductivity but more resistant to mechanical wear or abrasion than the brass of which the bulk of the contacts 5 will be made. This is accomplished by seating or otherwise fixing in the tip 30 of each contact 27, flush with its front end 28, an insert 38 of such material, the insert being of cylindrical or other suitable shape and providing at the end 28 an area sufficient to maintain contact with a like insert in a mating contact over the range of movement permitted by the mechanical couplers 3.

The electrical leads 39 to the several contacts 27, may be soldered but preferably are releasably connected to the contacts by suitable means such as that illustrated in 15 which the stem 31 of each contact is radially apertured adjacent its rear end to receive the end of its lead and a set screw 40 in the rear end of the stem and carrying a lock nut 41 locks the lead to the contact. However, regardless of the form of their individual connection to the contacts 27, it is necessary to the intended functioning of the coupler 1 that the leads 39 to all the contacts be makeable and breakable in unison by connecting them in advance of the contacts to a readily accessible, common quick-disconnect or junction 42. A particularly suitable 25 quick-disconnect is the illustrated plug connector 42 which has its housing, receptacle or outlet box 43 mounted within the box 6 on the latter's rear wall 44. Access to the connector 42 is had through an opening 45 in the outer side wall 46 of the box which normally is closed by a 30 cover plate 47 bolted or otherwise releasably secured to the wall.

The outlet box 43 of the illustrated plug connector 42 is attached to the rear wall 44 by an externally threaded flanged bushing 48 and nut 49 and the leads 50 from 35 the drum switch or other source, corresponding to and forming continuations of the leads 39, are lead in a bundle through the bushing into the receptacle. Within the receptacle 43 the leads 50 are separated and connected to individual spring sockets 51 mounted in an insulator plate 40 52 fixed in the receptacle. Conversely, each of the leads 39 connects to a prong or pin 53 mounted in an insulating plug 54 releasably fittable into the open outer end 55 of the receptacle. To ensure that on insertion of the plug 54 into the receptacle 43 each prong 53 will be received in or mate or interfit with the proper socket 51, the prongs and sockets may be arranged correspondingly but unevenly or in imbalance about the plate 52 and the plug so as to match or align in only one rotative 45 position of the plug. Alternatively, the plug 54, as illustrated, may carry a tongue or key 56 of T or other suitable shape which, when fitted into a correspondingly configured slot 57 in the plate 52, automatically aligns the prongs 53 and the sockets 51.

As in a conventional automatic electric coupler, the contacts 27 are protected from the elements when not in use by a weather shield or cover 58 which in closed position engages or seats against a rubber sealing gasket 59 surrounding the head 15 of the insulator block 14 and in this case conveniently mounted on the retainer 17. Conventionally, the shield 58 has arms 60 vertically embracing the box 6 and pivoted on a vertically disposed rod 61 fixed, outwardly off-center, to the back of the box. Normally held in closed position by a torsion spring 62 anchored to one or each end of the rod 61 and acting on the adjoining arm 60, the shield 58 is automatically swung or kicked to open, out-of-the-way position, on contact in a coupling operation with the shield of a mating coupler, because of the off-center position of its pivot and special contour of its outer face 63. Assurance that the same action will occur in a coupling operation with the couplers initially misaligned is obtained by providing the shield with the usual lever or striker arm 64 fixed to its outer side.

Constructed in the above manner, the improved automatic electric coupler 1 operates at least as well as prior

couplers in automatically connecting and disconnecting train electric service lines. However, its main advantage over prior couplers is in maintenance. Not only are the preferred contact pins 27 as effective and much longer lived than the usual pins by virtue of their wear-resistant inserts 38, but the mounting of the pins on an insulator block 14 which is removable simply by knocking out the wedges 24 holding it in place, in conjunction with the readily accessible quick-disconnect 42 for the electrical leads 39, enables the block, pins and plug 54 to be removed and replaced as a unit in a matter of minutes. By replacing a defective coupler with a like unit and sending the defective coupler to the shop for repair, it therefore is possible to repair the coupler at leisure, while limiting to a few minutes the down-time of a car attributable to such a defect. And, even in the shop, the preferred form of coupler, in which the leads are releasably connected to the pins, requires a minimum of time and skill to replace defective pins. Too, the removability of the block, pins and plug as a unit enables a coupler to be maintained without disturbing the mounting of its box 6 on the associated mechanical coupler 3 and thus the alignment of the coupler and, simply by using a block having the proper number and arrangement of pins and a corresponding plug, the coupler can be adapted at will to changes in the electric service lines. By contrast, the insulator block in prior couplers is difficult to remove and can be removed with the contact pins only by individually disconnecting the latter. As a consequence, maintenance of prior couplers is a difficult and time-consuming job which ordinarily is performed at the car and correspondingly delays the car's return to service.

From the above-detailed description, it will be apparent that there has been provided an improved automatic electric coupler for an automatic railway coupler assembly which is at least the equal of prior couplers in operation and far superior thereto in maintenance. It should be understood that the described and disclosed embodiment is merely exemplary of the invention and that all modifications are intended to be included that do not depart from the spirit of the invention or the scope of the appended claims.

Having described my invention, I claim:

1. An automatic electric coupler for a railway car comprising a housing having an open front end, a backing flange fixed to and instanding from sides of said housing inside said end, an insulator block inserted into said housing through said end and seated therein against said flange, a plurality of contact pins mounted in said block, a retainer frame engaging an outer face of said block and spaced from said pins, and means acting on an outer face of said retainer frame and releasably connected to said housing for releasably locking said block between said frame and said flange.

2. An automatic electric coupler for a railway car comprising a housing having an open front end, a backing flange fixed to and instanding from sides of said housing inside said end, an insulator block inserted into said housing through said end and seated therein against said flange, a plurality of contact pins mounted in said block, a retainer engaging said block and spaced thereby from said pins and outwardly from said flange, post means fixed to said housing and projecting through said block and retainer, and knock-out wedge means in said post means outwardly of and acting on said retainer for releasably locking said block in said housing between said retainer and flange.

3. An automatic electric coupler for a railway car comprising a housing, an insulator block removably mounted in said housing, a plurality of laterally spaced contact pins mounted in and normally projecting out-

wardly beyond an outer end of said block, a conductive relatively more wear-resistant insert in and flush with an outer end of each pin, a lead to each pin, and quick disconnect means in said housing, said disconnect means including plug means carrying a plurality of contacts individually connected by said leads to said pins, and outlet means carrying a plurality of contacts individually connected to electric lines, said plug and outlet contacts being correspondingly arranged and releasably interfitted for enabling said block, pins, leads and plug means to be removed as a unit from said housing.

4. An automatic electric coupler for a railway car comprising a housing, an insulator block removably mounted in said housing, said block having a plurality of laterally spaced perforations extending therethrough substantially normal to an outer end thereof, a plurality of unitary contact pins each axially slideable in and normally projecting beyond opposite ends of one of said perforations, a conductive relatively more wear-resistant insert in and flush with an outer end of each pin, a lead connected to each pin inwardly of said block, and quick disconnect means in said housing and releasably connecting said leads to related electric lines for enabling said block, pins, leads and part of said disconnect means to be removed as a unit from said housing.

5. An automatic electric coupler for a railway car comprising a housing, an insulator block removably mounted in said housing, a plurality of laterally spaced contact pins slideable axially in and normally projecting beyond an outer end of said block, and a conductive relatively more wear-resistant insert in and flush with an outer end of each pin.

6. An automatic electric coupler for a railway car comprising a housing, an insulator block releasably mounted in an otherwise open outer end of said housing, said block including a main part and a rear part initially separate from and bonded to a rear end of said main part, a plurality of laterally spaced apertures in said block and each having a front portion and an axially aligned relatively restricted rear portion extending respectively through said main and rear parts of said block and formed therein in the separate condition thereof, a unitary contact pin axially shiftable in and normally extending beyond opposite ends of each aperture and having a stem and an enlarged abutment respectively slideably received in the rear and front portions thereof, spring means in each aperture and acting between said abutment and said rear part of said block for yieldably resisting inward movement of the related pin, means on each pin inwardly on said block for limiting outward movement thereof, and a conductive relatively more wear-resistant insert fixed in and flush with an outer end of each pin.
